UNITED STATES PATENT OFFICE.

GEORGE E. R. ROTHENBUCHER, OF BROOKLYN, NEW YORK.

COMBINATION-WRENCH.

SPECIFICATION forming part of Letters Patent No. 703,741, dated July 1, 1902.

Application filed December 17, 1900. Serial No. 40,145. (No model.)

To all whom it may concern:

Be it known that I, GEORGE E. R. ROTHENBUCHER, a citizen of the United States, and a resident of New York, Brooklyn borough, in the county of Kings and State of New York, have invented certain new and useful Improvements in Combination-Wrenches, which improvements are fully set forth in the following specification and accompanying drawings, in which—

Figure 1 is a side elevation view of a combination-wrench constructed in accordance with my invention. Fig. 2 is a fragmentary elevation view illustrating the construction of the body portion of said wrench at the rear end thereof. Fig. 3 is a face view of the keeper which I employ for locking the wrench-handle and co-operating parts at the rear end of the wrench-body. Fig. 4 is a rear end view of the body portion of the wrench. Fig. 5 is a central longitudinal section of the wrench. Fig. 6 is a transverse section taken through the handle of my improved wrench.

Similar reference - numerals denote like parts throughout the several views of the drawings.

This invention relates to improvements in devices of that class commonly known as "combination-wrenches," each of which while adapted for use after the manner of an ordinary wrench embodies parts which render the wrench available for a plurality of purposes.

The object of this invention is to provide an implement of the type above indicated which shall combine the characteristics of the well-known "Stilson" wrench, a so-called "pipe-wrench," and a so-called "pipe-cutting" wrench, which shall be simple, cheap, and novel as regards construction and which shall possess certain well-defined advantages over prior analogous devices.

The invention consists in the employment of certain novelly-formed parts, in the novel disposition and arrangement of the various parts, in certain combinations of the latter, and in certain details of construction, all of which will be specifically referred to herein-after and set forth in the appended claims.

Having reference to the accompanying drawings, 2 denotes the body of the wrench of metal and having a central bore 2', enlarged

as to diameter at its respective ends to form the spindle-socket 2", and the cutter-socket 2'", the latter being angular in cross-section by preference.

3 is a spindle, the enlarged portion of which occupies the socket 2", and on the shank thereof is mounted the handle 3', held firmly in place and against rotation independently of said spindle by means of the nut 3" in the usual manner.

4 is a keeper employed for locking the spindle 3 with the handle carried thereby at the rear end of the body 2, and between said keeper and said handle there is located a ferrule 4'. The keeper 4 is let onto the spindle 3, from the rear end thereof, prior to the mounting on said spindle of the handle 3' and the ferrule 4', the said keeper being free to rotate on the spindle 3, though held against longitudinal movement or displacement therealong by the boss or shoulder 4" in one direction and by the ferrule 4' in the opposite direction. When the parts 3, 3', and 4' are assembled and locked together by the nut 3", they constitute in all essentials a unit and operate accordingly.

It will be seen by referring to Fig. 2 that the body 2 terminates at its rear end in a reduced portion, and this reduced portion is provided with an integral engaging lip 5, forming a transverse open-ended recess 5' between said lip and the adjacent shoulder of the body 2, formed by reducing the end of said body, and the inner face of said lip is formed slightly out of parallel with the said shoulder of the body 2. I purpose providing the reduced portion of the body 2 with at least two of the lips 5, one located diametrically opposite to the other.

The keeper 4 has a suitable central opening to admit of its being mounted on the spindle 3 and an interior lateral recess forming the upper and lower inwardly-extending flanges 6 6', and when the keeper 4 is in position for locking the spindle 3 to the body 2 the flange 6 occupies the recess 5' and binds between the lip 5 and the adjacent shoulder of the body 2. The inner face of the flange 6 is slightly inclined to correspond substantially with the inclined face of the lip 5.

The diameter of the opening in the keeper

4, at the upper face thereof, is primarily substantially the same as the diameter of the reduced portion of the body 2 and is sufficient to allow the shoulder 4" to pass to the interior of the keeper 4 when the latter is adjusted upon the spindle 3, and the flange 6 is suitably cut away, as at 7 7", to increase the diameter of said keeper-opening in one direction, and thus permit the passage of the 5 lip or lips 5 to the interior of said keeper when the latter is primarily adjusted upon the reduced portion of the body 2. When said keeper is thus adjusted upon the reduced portion of the body 2, the flange 6 may 10 be caused to bind between the lip 5 and the adjacent shoulder of the body 2, as above mentioned, by suitably turning said keeper on the reduced portion of said body. This 15 operation results in firmly locking the spindle 3, with its accompanying handle, to the body 2.

The spindle 3 is provided with a central bore at its enlarged end suitably threaded to receive the threaded portion of the cutter-carrier 8, which is provided with a clip, as 20 shown, in which is rotatably mounted a disk-cutter 8', as on the shaft 8", which latter bears at its respective ends in the opposing members 9 9' of said clip, as will be readily 25 understood. The cutter-socket 2"" being angular in cross-section, the clip members 9 9' obviate any appreciable rotary movement of the cutter-carrier 8.

From the foregoing description of the parts 30 under consideration it will be seen that in order to impart a longitudinal movement to the cutter-carrier 8, so as, for instance, to cause the cutting edge of the cutter 8' to project above the edge of the socket 2", the 35 keeper 4 is turned somewhat out of its locked position, but not sufficient to allow the lip or lips 5 to escape therefrom, and the handle 3' is rotated in the direction to unscrew the carrier 8 from the spindle 3, and since the 40 latter may not now recede or escape from its socket 2" the carrier 8 will move longitudinally away from the spindle 3 and carry the cutter 8' outward from its socket at the will of the user. Now by still holding the 45 keeper 4 in its liberated position, as stated, and reversely rotating the handle 3' the carrier 8 may be returned to its normal position and likewise the cutter 8' to its socket, whereupon by duly rotating the keeper 4 all 50 movable parts thus far described may be locked in their normal positions, and it will be seen that should the keeper 4 be rotated, so as to cause the cut-away portion or portions of the flange 6 to register with the lip 55 or lips 5, the handle 3', ferrule 4', spindle 3, and keeper 4 may be detached as a unit from the carrier 8 by suitably rotating said handle. When in its normal position, further return 60 movement of the carrier 8 is limited by reason of the clip members 9 9', carried thereby, being of suitable dimensions to prevent the

entrance thereof to the bore of the body 2 and to cause them to engage the bottom of the cutter-socket 2"".

The threaded adjustable shank 10, cradle 70 10', and adjusting-nut 10" are of ordinary and well-known construction, save that the cradle 10' is arranged to swing on a pivot, as 11, toward and away from the body 2, the swinging movement thereof away from said body 75 being limited by the stop or stops 11', preferably formed integral with the body 2. Normally the cradle 10' is locked at the limit of its movement away from the body 2 by means of the lock-lever or analogous device 11", 80 suitably fulcrumed, as at 12. When this lever is moved, as to the position indicated by dotted lines in Fig. 1, the cradle 10 may be swung somewhat from the position it occupies in Fig. 1 and which is its normal position toward the body 2, and the purpose of this movement of the cradle 10' will be explained hereinafter. In practice I purpose to employ a pair of stops, such as 11', one at each side of the body 2, and a pair of lock-levers, such as 11", also one at each side of the body 2, for respectively engaging said stops.

The head 12' of the shank 10 has a recess 12" opening toward the body 2, and there is located in said recess a pair of rollers 13 13', 95 adapted to rotate, as on the shafts 14 14'. The rollers 13 13' are normally covered by the removable jaw 13", here shown as having a roughened face, though the face thereof may be smooth, when desired. The jaw 13" is dovetailed to the head 12', as shown, and to aid in the retention of said jaw in place for service I employ a stop, as 14", here shown as spring-actuated and let into a hole or recess formed in the head 12'. 100

The wrench is provided with a further removable jaw 15, dovetailed to the end of the body 2, as shown, and to aid in the retention of this jaw in place for service I employ a further stop 15', corresponding in all essentials with the stop 14". 105

The jaw 15 seats fully upon the material of the body 2, surrounding the cutter-socket 12""", and as the rollers 13 13' project somewhat from the recess 12" it is essential that the jaw 13" be cut away to provide space for the projecting portions of said rollers. In this connection I prefer to form the back of the jaw 13" substantially as shown in the drawings, to the end that said jaw may be 115 provided with a central transverse rib, as 15", which will normally engage the head 12' at the sides of the recess 12" and materially strengthen said jaw.

When it is desired to cut an object circular in cross-section, as a piece of pipe or tube, it will be seen that the rollers 13 13' serve to hold the cutter 8' centered to said object at all times during the operation of cutting. 125

When it is desired to make use of the wrench 130 as a so-called "pipe-wrench," the swinging movement of the cradle 10' is desirable, as

thereby the jaws 18" and 15 may be separated and disengaged from the object between them should said jaws become unduly set against said object in using the wrench.

5 From the foregoing description of my device it will be seen that the same is particularly well adapted for the purpose for which it is designed and, further, that it may be modified to some extent without material departure from the spirit and principle of my invention.

Having fully described my invention, what I claim, and desire to secure by Letters Patent, is—

15 1. A device of the class herein described comprising a body provided with a reduced portion having an engaging lip, and with a spindle-socket, a spindle within said socket and having a boss, and a keeper on said spindle at the outer side of said boss, the said keeper having a flange at one face thereof adapted to engage said lip and lock said spindle against displacement from said socket.

20 2. A device of the class herein described comprising a hollow body; a cutter-carrier within said body, and therein movable longitudinally; means for holding said carrier against a rotary movement; a spindle having a threaded engagement with said carrier; and 25 a rotatable keeper capable, when in its locked position, of normally holding said spindle against movement independent of said body, and of permitting a rotary movement of said spindle though loosely holding said spindle

against displacement from said body, when 35 the said keeper is eased out of its locked position.

3. A device of the class herein described comprising a body, a cradle having a swinging movement with respect to said body, 40 means for limiting the movement of said cradle away from said body, and a suitably-fulcrumed lever for locking said cradle at the limit of its movement away from said body.

4. A device of the class herein described 45 comprising a hollow body, a carrier within and longitudinally movable with respect to said body, a rotary disk-cutter on said carrier, means for imparting a longitudinal movement to said carrier, means for locking said carrier 50 when moved to any desired position, a cradle having a swinging movement with respect to said body, means for limiting the movement of said cradle away from said body, a suitably-fulcrumed lever for locking said cradle 55 at the limit of its movement away from said body, an adjustable shank in said cradle, the said shank having a recessed head lying opposite to said cutter, and a pair of rollers in the recess of said head, the said rollers being located one on each side of the center line of said cutter, substantially as herein described.
